UNITED STATES PATENT OFFICE.

JOHN H. RAFFERTY, OF WORCESTER, MASSACHUSETTS.

BRIDLE.

SPECIFICATION forming part of Letters Patent No. 431,396, dated July 1, 1890.

Application filed September 19, 1889. Serial No. 324,424. (No model.)

To all whom it may concern:

Be it known that I, JOHN H. RAFFERTY, of Worcester, in the county of Worcester and State of Massachusetts, have invented a new 5 and Improved Combined Bridle and Check, of which the following is a full, clear, and exact description.

My invention relates to bridles for horses or other animals, and has for its object to provide a simple and comparatively inexpensive 10 combined bridle and check device readily convertible for service with either an overdraw checkrein or a side checkrein, and adjustable also to fit animals' heads of different 15 sizes, the whole making an elegant, light, and very substantial bridle structure.

The invention consists in certain novel features of construction and combinations of parts of the bridle and check, all as hereinabove described and claimed.

Reference is to be had to the accompanying drawings, forming a part of this specification, in which similar letters of reference indicate corresponding parts in all the figures.

25 Figure 1 is a perspective view of my improved combined bridle and check. Fig. 2 is an enlarged detail sectional plan view taken on the line *xx* in Fig. 1. Fig. 3 is a front or edge view of one of the clasps which connect the bridle-straps with the bit-rings and partly broken away. Fig. 4 is an inside face view of one of the two sections of the strap and bit-ring clasp; and Fig. 5 is a sectional view taken through the clasp on the line *yy* in Fig. 3, and shows the bridle-strap in side elevation.

Aside from its metal trimmings and bit my improved bridle, excepting the brow-band, is or may be made practically of one continuous leather strap, and could be made of one piece were the hides or skins long enough for the purpose, and the checkrein-strap, made partly of the leather straps forming the bridle, is stitched fast to these bridle-straps, so that 45 the whole structure of bridle and checkrein may properly be said to consist, mainly, of one continuous piece made and arranged as follows: I take a leather strap or band about as wide throughout as the crown-strap *A* of 50 the bridle, and which may be made in two parts joined at the center of the crown-strap. From two points *a a* at the lower ends or

sides of the crown-strap the strap is slit in two centrally lengthwise, thereby forming two long narrow straps. The rear pair *B B'* 55 of these narrow straps are then cut off to proper length, and are provided with a buckle *b* and loop *b'*, and thus constitute the throat-latch of the bridle. The front pair of these straps are extended downward and forward 60 to form the cheek-pieces *C C'*, and the straps are then bent around or doubled upon themselves at *c c'* and within **U**-shaped cavities or openings of two clasps *H H*, made alike, and as presently described, and to which the 65 rings *i i* of the bit *I* are connected. From the clasps *H H* the two straps are extended upward and toward each other to form the two face-straps *D D'*, which, when the bridle is to have an overdraw-check, are held to 70 each other by a clip device *J* about at the center of the bridle, and from this clip the straps extend upward and diverge and pass as overdraw-checkreins through adjustable loops or rings *K K*, fixed in any approved 75 way to the crown-strap *A*, and made to open to allow removal of the straps *E E'* when converting from an overdraw to a side check in a manner presently described. From these 80 loops *K K* the straps *E E'* converge rearward and are united at *e* to the broad rear check strap or rein *F*, having a perforated billet *f*, allowing its connection to the water-hook of the harness saddle or girth. (Not shown in the drawings.) 85

The clip *J* is made preferably of one piece of somewhat elastic metal, which may be opened to allow removal of it from the straps *D D'* when converting the bridle from an overdraw to a side check. I prefer to lap the 90 ends of the clip onto each other and pass a screw *j* through them into a threaded hole in the rear of the clip, and whereby, when the screw is loosened, the clip may be adjusted to converge the face and overdraw straps at 95 the most advantageous place to present the best appearance on a horse having a larger or smaller head, and when the clip is thus adjusted by slipping it along on the straps the screw *j* is tightened to securely clamp them. 100 The clip is bent or shaped to conform as nearly as possible to the shape of the straps, as shown in Fig. 2 of the drawings. The loops or rings *K K* are of my own design, and con-

sist, substantially, of two open rings, one fitted for rotation on the other to allow opening of them, as shown at the right-hand loop, to withdraw the checkreins E E' or allow 5 their insertion at pleasure.

The brow-band G of the bridle is looped at opposite ends *g g* around the throat-latch straps B B' and through eyes *l l*, fixed to the inner faces of metal trimmings or escutcheons 10 L L, to which are fixed two snap-hook loops M M, having spring-closed latches *m m*, which may be pressed open to place the straps E E' into the snap-hooks when the overdraw-check 15 is to be converted into a side-check device. The bridle-clasps H are peculiarly made with two halves *h h*, preferably having a semi-circular cross-section and cast or pressed into a general U-form. (Clearly shown in the drawings.) Each of these parts *h* of the clasp is 20 provided at its center and lower middle portion with an open eye or ring *h'*, which ranges about at right angles with the main body of the part *h*, and at its shank near the point of connection with the body is provided with a 25 lateral slanting or tangential shoulder *h*², against which the beveled or inclined end *h*³ of the open eye or ring *h'*, of the opposing part *h* of the clasp is adapted to lock in such manner that the two rings *h' h'* of both parts 30 *h h* will together form a complete smooth round eye H', which receives a bit-ring of the bridle. The ends of the two limbs of the clasp halves or portions *h h* are tapered at *h*⁴ and screw-threaded at *h*⁵ next the taper, and 35 onto these threads *h*⁵ are adapted to be screwed a pair of milled nuts H² H², which have tapering outer ends, which crowd upon the tapered extremities *h*⁴ of the two halves of the clasp, and thereby bind them securely 40 upon the bight *c* of the bridle-straps, from which the cheek and face straps C D extend. When the retaining-nuts H² are thus applied, 45 the interlocking shoulders and extremities *h*² *h*³ coact to prevent a separation of the lower rounded portion of the divided main body of the clasp. To assure a perfectly-tight clamping 50 of the bridle-strap by the clasp, their tapered extremities *h*⁴ are beveled off or back a little from the general plane of the joint between the main body parts of the clasp, as 55 shown in Fig. 3 of the drawings, wherein the nut H² is partly broken away for this purpose.

It will be noticed that by simply removing the nuts H² from the split bodies of the clasps 60 the latter may easily be separated to allow them to be adjusted on bights *c c* of the bridle-straps produced farther from or nearer to the crown-strap A, whereby provision is made for lengthening or shortening the bridle to suit 65 animals having longer or shorter heads, and the screw *j* of the face-strap clip J will then be loosened to allow it to be adjusted at a new place to assure the best set of the straps on the face of the animal, and this adjustment of the clip J may be made at any time should it be desired to readjust the set or range of 70 the face-straps should the bridle already be

of proper length between the crown-strap and bit.

Fig. 1 of the drawings shows the bridle, 70 with the straps D D' E E' adjusted in the clip J and loops K K for service as an overdraw-check. To readjust these straps to serve as a side check, it is only necessary to disengage the billet *f* from the water-hook and remove the clip J, and then open the loops K K and lift the straps E' E' therefrom and slip them into the snap-hook loops M M, and then remove the clasp-nuts H² and separate the two clasps H H and turn the bights 80 *c c* of the straps half-way around and reapply the clasps, leaving the straps C to the front and the straps D to the rear to avoid crossing the straps or twisting the clasps, and the strap F may then be connected to the 85 water-hook, and the bridle then has a complete side-checkrein device. These operations may readily be reversed in order to again reconvert the bridle to provide it with the overdraw-check device. 90

I much prefer to give the bridle and check-straps B B', C C', D D', and E E' G a rounded form where possible; but this is not essential, as the clasps H and clip J may be shaped to fit straps of flat, square, or any other cross-sectional form, as will readily be understood. 95

Having thus fully described my invention, I claim as new and desire to secure by Letters Patent—

1. A bridle made with cheek and face pieces 100 of each side formed in one continuous strap connected with the crown-strap, combined with bent or U-shaped divided clasps holding the straps at their lower bends or bights, substantially as herein set forth. 105

2. A bridle made with the cheek and face pieces of each side formed in one continuous strap connected with the crown-strap, combined with U-shaped divided clasps holding the straps at their lower bends or bights, and 110 a bit held to the clasps, substantially as herein set forth.

3. A bridle made with the cheek and face pieces of each side formed in one continuous strap connected at one end to the crown-strap and extending rearward at the other ends to 115 form a checkrein, combined with clasps engaging the lower bends or bights of the straps and a bit held to the clasps, substantially as herein set forth. 120

4. A bridle made with the cheek and face pieces of each side formed in one continuous strap connected at one end to the crown-strap and extending rearward at the other ends to 125 form a checkrein, combined with bent or U-shaped divided clasps holding the straps at their lower bends or bights and a bit held to the clasps, substantially as herein set forth.

5. In a combined bridle and check, the cheek and face pieces of each side formed as 130 continuous straps connected at one end to the crown-strap and extending rearward at the other ends to form a checkrein, clasp devices holding the two straps at their lower bends

or bights, a bit held to the clasps, overdraw-check loops and side loops held to the crown-strap, and a detachable clip device adapted to the face-straps, substantially as described, 5 whereby the bridle may be adjusted with an overdraw-check or a side check, as set forth.

6. In a combined bridle and check, the cheek and face pieces of each side formed as continuous straps connected at one end to the 10 crown-strap and extending rearward at the other ends to form a checkrein, bent or **U**-shaped divided clasps holding the straps at their lower bends or bights, a bit held to the clasps, overdraw-check loops and side loops 15 held to the crown-strap, and a detachable clip device adapted to the face-straps, substantially as described, whereby the bridle may be adjusted with an overdraw-check or a side check and the strap-bights may be readjusted in the divided clasps to prevent twisting 20 of the straps when the overdraw-check is changed to a side check, as set forth.

7. The combination, in a bridle and check, of a crown-strap A, throat-latch B B', two 25 continuous straps C D E and C' D' E', connected to the crown-strap, a check-strap F, connected to the parts E E', divided clasps H H, clamping the bights c c of the straps C D C' D', a bit connected to the clasps, a brow-band G, and side loops adapted to receive the straps E E' as a side-checkrein device, substantially as herein set forth.

8. The combination, in a bridle and check, of a crown-strap A, throat-latch B B', two 35 continuous straps C D E and C' D' E', connected to the crown-strap, loops K K on the crown-strap, receiving the strap E E', a strap F, connected to the parts E E', divided clasps H H, clamping the bights c c of the straps C 40 D C' D', a detachable clip J, held to the face-straps D D', and a bit held to the clasps H H, substantially as described, for the purposes set forth.

9. In a bridle, the combination, with a 45 crown-strap and connected continuous straps

forming cheek, face, and check straps and doubled-in bights c c, substantially as specified, of divided clasps of **U** form, placed on said bights and provided with nuts at their extremities, substantially as herein set forth. 50

10. In a bridle, the combination, with a crown-strap and connected continuous straps forming cheek, face, and check straps and doubled-in bights c c, substantially as specified, of two-part clasps at said bights, provided at their extremities with clamping-nuts, and eyes connected to the clasp-bends to receive the bit, substantially as herein set forth. 55

11. In a combined bridle and check, the combination, with a crown-strap and connected continuous straps C D E C' D' E', forming cheek, face, and check straps, and bent or **U**-shaped divided clasps inclosing the bights c c of the straps, of an adjustable and detachable clip on the face-straps, substantially as herein set forth. 60

12. In a bridle, the combination, with a crown-strap and connected continuous straps forming cheek, face, and check straps and doubled-in bights c c, substantially as specified, of bent or **U**-shaped clasps formed with two parts h h, each having an open ring h', a shoulder h², and a beveled extremity h³, and detents holding the parts h h together, substantially as herein set forth. 70

13. In a bridle, the combination, with a crown-strap and connected continuous straps forming cheek, face, and check straps and doubled-in bights c c, substantially as specified, of clasps H, formed with two parts h h, each having an open ring h', an inclined shoulder h², a beveled extremity h³, and screw-threads h⁴, and nuts H², run upon said threads, substantially as herein set forth. 75
